LAMP

Joseph M. Feldman and Rolando S. Vasquez, Los Angeles, Calif., assignors to The Feldman Company, Los Angeles, Calif.

Filed Nov. 29, 1972, Ser. No. 310,660

Term of patent 14 years

Int. Cl. D26—05

U.S. Cl. D48—20 C

FIG. 1.

FIG. 2.

FIG. 3.

FIG. 4.

FIG. 1 is an isometric view of a lamp, showing our new design;

FIG. 2 is a side elevational view thereof, showing the side not shown in FIG. 1;

FIG. 3 is another side elevational view, looking from the right in FIG. 2; and

FIG. 4 is a greatly enlarged fragmentary sectional view of the globe portion of the lamp.

The bottom of the base of the lamp is plain.

We claim:

The ornamental design for a lamp, substantially as shown and described.
